UNITED STATES PATENT OFFICE.

JAMIE ABERCROMBIE, OF HOUSTON, AND NESBIT M. DUNMAN, OF WEST COLUMBIA, TEXAS.

COMBINATION WELL-PACKER AND SETTING-TOOL.

1,327,077.

Specification of Letters Patent.

Patented Jan. 6, 1920.

Application filed February 6, 1919. Serial No. 275,325.

To all whom it may concern:

Be it known that we, JAMIE ABERCROMBIE and NESBIT M. DUNMAN, citizens of the United States, residing at Houston and West Columbia, respectively, in the counties of Harris and Brazoria and State of Texas, have invented certain new and useful Improvements in Combination Well-Packers and Setting-Tools, of which the following is 10 a specification.

This invention relates to new and useful improvements in a combination well packer and setting tool.

One object of the invention is to provide a 15 well packer of the character described, which may be interposed between oil and water bearing strata in a well, so as to prevent the intermingling of the oil and water.

Another object of the invention is to provide a packer of the character described, which may be readily introduced between two concentric pipes, or between a pipe and the wall of the bore of a well, between oil 25 and water strata, to prevent the intermingling of the oil and water as above stated, or when placed above the oil strata to force the oil into the pipe through the well screen, and to prevent the same from traveling up 30 through the bore on the outside of the pipe.

A further feature of the invention resides in the provision of means for setting the packer, said means being removable when the packer is set.

With the above and other objects in view, the invention has particular relation to certain novel features of construction, operation and arrangement of parts, an example of which is given in this specification and 40 illustrated in the accompanying drawings, wherein:

Figure 1, is a side elevation of the complete device, shown partially in section along the longitudinal center line.

Fig. 2, is a transverse sectional view taken on the line 2—2 of Fig. 1, and

Fig. 3, is a side elevation of a modified form of the packer, shown partially in section along the longitudinal center line.

Referring now more particularly to the drawings, wherein like numerals of reference designate similar parts in each of the

figures, the numeral 1, refers to a pipe section, whose lower end is externally threaded for engagement with a well screen, or section 55 of pipe located beneath the packer, and swaged upon the lower end of this section above said threads is an annular ring 2, whose upper side is formed with an annular groove 3. The upper end of the section 2 60 is provided with right hand threads 4, extending a considerable distance along its length, and fitted over said upper end is a sleeve 5, which is easily movable along the section 1. The upper end of this sleeve 65 has the annular flange 6, whose under face is provided with an annular groove 7. Surrounding the pipe section 1, and the sleeve 5, is a packer element 8, preferably formed of fabric, which is wrapped therearound, and 70 is secured in place by means of the spiraled wire 9. The lower and upper ends of this packer element 8 are seated in, and confined by, corresponding grooves 3 and 7, and the sleeve 5 is of sufficient length to protect the 75 packer element 8 against coming into contact with and hanging upon the threads 4. As the sleeve 5 is forced downwardly, it is obvious that the packer element 8 will be forced to expand out against the surrounding pipe, or the walls of the bore, and will form a fluid tight joint therewith. Threaded upon the upper end of the pipe section 1, is a tubular member 10, having the internal 80 lengthwise ribs 11, which are spaced the required distance apart. The numeral 12 refers to an elongated nipple, whose upper end is formed into a joint member 13, provided for its attachment to the lower end of a string of pipe, and underneath said joint 90 member the nipple is reduced, and formed with left hand threads 14, provided for engagement with corresponding threads 15, formed in the upper end of the tubular member 10. Beneath the threads 14, the 95 nipple is reduced, and forms a blank, and carries the longitudinally peripheral ribs 16, which are spaced apart therearound, and of a width to readily pass between the ribs 11, and the upper and lower ends of the ribs 100 11 and 16, are oppositely beveled, as shown in Fig. 1.

Before the device is let down into the well, the packer is assembled, as shown in Fig. 1,

and the tubular member 10 is threaded upon the upper end thereof. The blank end of the nipple 12 is then inserted in the tubular member 10, the ribs 16 passing between the 5 ribs 11, said rib ends being beveled to prevent their abutting ends from engaging against each other, and facilitating the passage of the ribs 16, through between the ribs 11. The threaded section 14 is then screwed 10 into the threads 15, of the member 10, the ribs 16 being at this point below and out of engagement with the ribs 11, to permit the rotation of the nipple 12.

A sufficient number of joints of pipe are 15 attached to the lower end of the section 1, to bring the packer to the desired point in the bore, and a sufficient string of pipe is attached above to project above the surface of the ground. The string is then rotated to 20 the right, which will cause the disengagement of the threads 14, from the threads 15, and the string is then elevated sufficiently to carry the ribs 16 up between the ribs 11, and the string is then further rotated, screwing 25 the member 10 down against the upper end of the sleeve 5, and as rotation is continued, said sleeve will be forced downwardly causing the packer element 8 to bulge out against the surrounding pipe of the surrounding 30 wall of the well bore, all the way around, thus forming a water tight joint. The string of pipe carrying the nipple 12 may be then withdrawn from the bore, leaving the packer set in the well.

35 In Fig. 3, we have shown a modified form of the device, having the lower ring 2' swaged upon the lower end of the pipe section 1, above the threads thereof. The upper part of this ring tapers inwardly as 40 shown in Fig. 3. In this form, the sleeve 5 has the flange 6', formed integral with the upper end thereof, and having a downward taper. In this form, the packer element 8 consists of a sleeve formed of lead, or other 45 soft material, the tapering ends of the ring 2' and the flange 6' fitting within the corresponding ends of said packer 8'. As the sleeve 5 is forced downwardly, as hereinabove explained, said packer element 8 will 50 be expanded against the outer pipe, or the wall of the bore, forming a water tight joint as above explained.

As shown by Figs. 1 and 2, the nipple 12 has a water course 17, therethrough from 55 end to end, to permit water to be forced

down, into the bore, as the same may be required incident to operation.

What we claim is:

1. A packer for wells, including a pipe section, whose upper end is externally 60 threaded, an annular member fixed thereon near the lower end thereof, a longitudinally movable annular member mounted on said section and spaced from said fixed member, and formed into an extended sleeve, the facing sides of said members being formed with annular grooves, a sleeve-like packer element surrounding said section and sleeve interposed between said members and whose respective ends are seated in and confined by 70 the corresponding grooves, said sleeve holding said packer element out of contact with said threads and a means whereby said packer element may be expanded.

2. A packer for wells, including a pipe 75 section, whose upper end has external right hand threads, annular members spaced apart thereon, one of which is fixed thereto near its lower end and the other of which is longitudinally movable, said movable member being formed into an extended sleeve, a sleeve-like expandable packer element surrounding said section and sleeve, and interposed between said annular members, said sleeve holding said packer element out of contact 80 with said threads, a tubular member adapted to be threaded upon said section, against said movable annular member, said tubular member having internal longitudinal ribs spaced apart, and a nipple, a section of 85 which has external left hand threads, the remaining portion of said nipple being blank, said nipple being adapted to fit within said tubular member, the upper end of said tubular member being internally threaded to receive the threads of said nipple, a blank portion of the nipple being provided with peripheral longitudinal ribs adapted to pass between the ribs of the tubular member, said ribs, at times, interlocking whereby the rotation 90 of the nipple will be imparted to the tubular member.

In testimony whereof we have signed our names to this specification in the presence of two subscribing witnesses.

JAMIE ABERCROMBIE.
NESBIT M. DUNMAN.
